UNITED STATES PATENT OFFICE

107,253

DESIGN FOR A SHOE SOLE

Oswald M. Pick, Chicago, Ill., assignor to The Florsheim Shoe Company, Chicago, Ill., a corporation of Illinois

Application December 24, 1936, Serial No. 66,729

Term of patent 3½ years

To all whom it may concern:

Be it known that I, Oswald M. Pick, a citizen of the United States and a resident of the city of Chicago, in the county of Cook and State of Illinois, have invented a new, original, and ornamental Design for a Shoe Sole or Similar Article, of which the following is a specification, reference being had to the accompanying drawing, forming a part thereof.

On the drawing:

The figure is a bottom plan view of a shoe sole showing my new design, the sole being of conventional thickness.

The characteristic feature of the design resides in the provision of an ornamental border or marginal portion of the sole of a color contrasting with that of the remainder of the sole and tapering in width to a point at the toe and to a narrow band at the heel, the border co-operating with a longitudinally extending line on the sole to produce the appearance of a sole having a width less than the actual width.

I claim:

The ornamental design for a shoe sole or a similar article as shown and described.

OSWALD M. PICK.
